FIG. 1

FIG. 2

UNITED STATES PATENT OFFICE

2,646,661

SELF-WINDING TIMEPIECE

Otto Von Aesch, Fontainemelon, Switzerland, assignor to Fabrique d'Horlogerie de Fontainemelon S. A., Fontainemelon, Canton of Neuchatel, Switzerland, a firm of Switzerland

Application June 21, 1952, Serial No. 294,867
In Switzerland August 29, 1951

7 Claims. (Cl. 58—82)

1

My invention has for its object a self-winding time-piece, the winding of which is performed by means of an oscillatory mass, said time-piece being of the type including a pinion on the spindle carrying which is provided with a threaded part screwed inside a nut that is held against axial shifting, said nut being driven into rotation by the barrel or the barrel spindle while the pinion is driven correspondingly by the barrel spindle or the barrel in a manner such that the pinion-carrying spindle is shifted axially in one direction when the time-piece is being wound up and in the opposite direction when the spring expands.

My improved time-piece is characterized by the fact that the pinion-carrying spindle is parallel with the axis of the time-piece mechanism and its end, located near the cocks or bridge-pieces, is adapted to engage a recess in the oscillatory mass in order to lock the latter against movement when the spring has been completely wound up, while its other end is shaped so as to control the movement of an indicator of the degree of expansion of the spring.

I have illustrated by way of example in accompanying drawings a preferred embodiment of the object of my invention.

Figure 1 is a plan view of a part of the time-piece.

Figure 2 is a cross-section, passing through line II—II of Figure 1 and through the barrel spindle, of a part of said time-piece.

The frame of the time-piece illustrated includes a first plate 1, a barrel bridge-piece or cock 2 and a bridge-piece or cock 3 for the winding up means. The spindle 4 of the barrel is revolvably held inside the plate 1 and inside the cock 2. The barrel or spring-box is designated by the reference number 5 and its cover by the reference number 6. The actual spring is not illustrated. The end 4a of the barrel spindle projecting above the cock 2 is square and carries the spring-winding ratchet wheel 7 that is driven through a gear-work, that is not illustrated, by the winding up oscillatory mass 8. The spindle 4 carries furthermore a toothed wheel 9 located above said ratchet wheel 7 and meshing with a wheel 10, the hub 10a of which is screwed over a threaded section 11a of a spindle 11 that is parallel with the barrel spindle and is revolvably carried, on one hand, in the plate 1 and, on the other, in the cock 3 of the self-winding means. The spindle 11 is mounted so as to be capable of being shifted axially and it carries a pinion 12 keyed thereto and that meshes with the teeth 13 on the barrel or spring-box. These teeth 13 in-

2

clude only three teeth at 120° from one another. The wheel 10 is prevented from being shifted axially by reason of the fact that it abuts through its lower surface against the ratchet wheel 7 and against a section of the barrel cock 2 while its upper surface engages the cooperating surface of the cock 3.

When the winding up of the spring is at an end, the spindle 4 driven by the ratchet wheel 7 controlled by the oscillatory mass constrains the wheel 9 to rotate and to drive in its turn the wheel 10. The latter plays the part of a nut and urges the spindle 11 to move in the direction facing the upper part of the drawing. In contradistinction, when the spring expands, the spring barrel produces through its teeth 13 a rotation of the pinion 12 and consequently of the spindle 11. As the wheel 10 is then stationary, the spindle 11 unscrews and moves downwardly.

The oscillatory winding up mass 8 is provided with a perforation 14 which for certain angular positions of said oscillatory mass is in co-axial alignment with the spindle 11. The upper end 11b of the spindle 11 is rounded and when the spring is completely wound up, the spindle 11 has moved upwardly to a sufficient extent for its end 11b to be capable of entering the perforation 14 and of locking the mass against movement, whereby the spring is protected against any exaggerated tensioning. It is then necessary to wait for the spring to slightly expand and consequently for the spindle 11 to move downwardly by a small amount that is sufficient for the mass to be released and for the rewinding of the spring to be resumed.

The lower end 11c of the spindle 11 is fitted inside an opening 15 in a rocking lever 16 pivotally secured over a pivot 17 screwed into the plate 1. This rocking lever that is carried immediately on the inside of the dial, that is not illustrated, is provided at 16a with teeth cooperating with a toothed sector 18 keyed to a spindle 19 carrying an indicator hand 20. A return spring 21 urges a section of the edge of the opening 15 in said rocking lever against the conical end 11c of the spindle 11, whereby the said rocking lever is constrained to rock during the axial movements of the spindle 11. These movements depend on the amount by which the barrel spring is wound and consequently the hand 20 controlled thereby gives an indication as to the degree of expansion of the spring.

What I claim is:

1. In a time-piece, the combination of an oscillatory winding up mass, provided with an ec-

centric opening, a barrel, a barrel spindle, a spring contained in said barrel and connected at its ends with the barrel and with the barrel spring respectively, a spindle parallel with the barrel spindle at a distance therefrom equal to the eccentricity of the opening in the oscillatory mass, a transmission through which the oscillatory mass controls the barrel spindle, said spindle including a threaded section, a nut engaging said threaded section, means preventing the axial movement of said nut, a pinion rigid with the second spindle, means whereby the barrel and the barrel spindle control respectively the rotation of one of the two following parts, the pinion and the nut, to constrain the second spindle to assume a relative axial movement with reference to the nut when the barrel and barrel spindle assume a relative rotary movement with reference to each other, said second spindle being adapted to engage the opening on the oscillatory mass whenever the spring is completely wound and consequently the barrel spindle has come to the end of its relative angular movement with reference to the barrel.

2. In a time-piece, the combination of an oscillatory winding up mass, provided with an eccentric opening, a barrel, a barrel spindle, a spring contained in said barrel and connected at its ends with the barrel and with the barrel spring respectively, a spindle parallel with the barrel spindle including a threaded section and lying at a distance from said spindle equal to the eccentricity of the opening in the oscillatory mass, a transmission through which the oscillatory mass controls the barrel spindle, a nut engaging said threaded section, means preventing the axial movement of said nut, a pinion rigid with the second spindle, means whereby the barrel and the barrel spindle control respectively the rotation of one of the two following parts, the pinion and the nut, to constrain the second spindle to assume a relative axial movement with reference to the nut when the barrel and barrel spindle assume a relative rotary movement with reference to each other, said second spindle being adapted to engage the opening in the oscillatory mass whenever the spring is completely wound and consequently the barrel spindle has come to the end of its relative angular movement with reference to the barrel, and an indicator of the extent of expansion of the spring controlled by the longitudinal movement of said second spindle.

3. In a time-piece, the combination of an oscillatory winding up mass, provided with an eccentric opening, a barrel, a barrel spindle, a spring contained in said barrel and connected at its ends with the barrel and with the barrel spring respectively, a spindle parallel with the barrel spindle, including a threaded section and lying at a distance from the spindle equal to the eccentricity of the opening in the oscillatory mass, a transmission through which the oscillatory mass controls the barrel spindle, a nut engaging said threaded section, means preventing the axial movement of said nut, a pinion rigid with the second spindle, a plurality of teeth rigid with the outer periphery of said barrel and adapted to successively engage the pinion upon rotation of the barrel, means whereby the transmission between the oscillatory mass and the barrel spindle controls the angular position of the nut to constrain the second spindle to assume a relative axial movement with reference to the nut when the barrel spindle assumes a relative rotary movement with reference to the barrel, said second

spindle being adapted to engage the opening on the oscillatory mass whenever the spring is completely wound and consequently the barrel spindle has come to the end of its relative angular movement with reference to the barrel.

4. In a time-piece, the combination of an oscillatory winding up mass, provided with an eccentric opening, a barrel, a barrel spindle, a spring contained in said barrel and connected at its ends with the barrel and with the barrel spindle respectively, a spindle parallel with the barrel spindle including a threaded section and lying at a distance from the first spindle equal to the eccentricity of the opening in the oscillatory mass, a transmission through which the oscillatory mass controls the barrel spindle, a nut engaging said threaded section, means preventing the axial movement of said nut, a pinion rigid with the second spindle, means whereby the barrel and the barrel spindle control respectively the rotation of one of the two following parts, the pinion and the nut, to constrain the second spindle to assume a relative axial movement with reference to the nut when the barrel and barrel spindle assume a relative rotary movement with reference to each other, said second spindle being adapted to engage the opening on the oscillatory mass whenever the spring is completely wound and consequently the barrel spindle has come to the end of its relative angular movement with reference to the barrel, the end of said second spindle opposed to the oscillatory mass being conical, an indicator of degree of expansion of the barrel spring and a lever controlling the angular position of said indicator and provided with an opening engaged to a varying extent by the conical end of the second spindle according to the axial position of said second spindle.

5. In a time-piece, the combination of an oscillatory winding up mass provided with an eccentric opening, a spring-box, a spring-box spindle, a spring contained in said spring-box and the ends of which are secured to the latter and to the spring-box spindle, a ratchet wheel rigid with the spring-box spindle on the outside of the spring-box, a second spindle parallel with the spring-box spindle on the outside of the spring-box and at a distance from said spring-box spindle equal to the eccentricity of the opening in the oscillatory mass, and including a threaded section, a nut-shaped toothed wheel engaged by said threaded section, a pinion coaxially rigid with the ratchet wheel and meshing with the nut-shaped wheel, a cock for the spring-box, a second cock for the oscillatory mass, the nut-shaped wheel being fitted with a slight clearance between the two cocks, a transmission operatively connecting the oscillatory winding up mass with the ratchet wheel and a pinion rigid with the second spindle and the rotation of which is controlled by the rotation of the spring-box, the relative movement of the spring-box and spring-box spindle producing a helical movement of the second spindle with reference to the nut-shaped wheel into and out of register with the eccentric opening in the oscillatory winding up mass.

6. In a time-piece, the combination of an oscillatory winding up mass provided with an eccentric opening, a spring-box, a spring-box spindle, a spring contained in said spring-box and the ends of which are secured to the latter and to the spring-box spindle, a ratchet wheel rigid with the spring-box spindle on the outside of the spring-box, a second spindle parallel with the spring-box spindle on the outside of the spring-

box and at a distance from said spring-box spindle equal to the eccentricity of the opening in the oscillatory mass, and including a threaded section, a nut-shaped toothed wheel engaged by said threaded section, a pinion coaxially rigid with the ratchet wheel and meshing with the nut-shaped wheel, a cock for the spring-box, a second cock for the oscillatory mass, the nut-shaped wheel being fitted with a slight clearance between the two cocks, a transmission operatively connecting the oscillatory winding up mass with the ratchet wheel and a pinion rigid with the second spindle and the rotation of which is controlled by the rotation of the spring-box, the relative movement of the spring-box spindle producing a helical movement of the second spindle with reference to the nut-shaped wheel into and out of register with the eccentric opening in the oscillatory winding up mass, the end of the second spindle opposed to the oscillatory mass being conical, a stationary plate, a hand pivotally secured to the plate and indicating the degree of expansion of the spring, a toothed sector, coaxially rigid with said hand, a lever pivotally secured to the plate and one end of which is toothed for engagement with said sector, the other end of the lever being recessed for engagement to a varying extent by the conical end of the second spindle according to the axial position assumed by the latter.

7. In a time-piece, the combination of an oscillatory winding up mass provided with an eccentric opening, a spring-box, a spring-box spindle, a spring contained in said spring-box and the

5 ends of which are secured to the latter and to the spring-box spindle, a ratchet wheel rigid with the spring-box spindle on the outside of the spring-box, a second spindle parallel with the spring-box spindle on the outside of the spring-box and at a distance from said spring-box spindle equal to the eccentricity of the opening in the oscillatory mass, and including a threaded section, 10 a nut engaged by the threaded section, a pinion coaxially rigid with said nut, a transmission controlled by the oscillatory mass and controlling both last mentioned pinion and the ratchet wheel, three teeth at the periphery of the spring-box, and a pinion rigid with the second spindle and controlled by the teeth on the spring-box upon rotation of the latter, the relative movement of the spring-box and spring-box spindle producing a helical movement of the second spindle with reference to the nut-shaped wheel into 15 and out of register with the eccentric opening in the oscillatory winding up mass.
